DESIGN FOR A JEWELRY CHARM

Charles Kiaschek, Brooklyn, N. Y., and George Kiaschek, London, England

Application February 19, 1948, Serial No. 144,607

Term of patent 3½ years

(Cl. D45—17)

To all whom it may concern:

Be it known that we, Charles Kiaschek and George Kiaschek, respectively a citizen of the United States of America, and a subject of the King of Great Britain, residing respectively at Brooklyn, in the county of Kings and State of New York; and London, England, have invented a new, original, and ornamental Design for A Jewelry Charm, of which the following is a specification, reference being had to the accompanying drawing, forming part thereof.

In the drawing

Fig. 1 is a front elevational view of a jewelry charm, showing our new design; the opposite side of the charm being identical;

Fig. 2 is a side elevational view thereof; and Fig. 3 is a bottom plan view.

We claim:

The ornamental design for a jewelry charm, substantially as shown and described.

CHARLES KIASCHEK.
GEORGE KIASHEK.
